UNITED STATES PATENT OFFICE

REX R. WAGGONER, OF SANTA MONICA, CALIFORNIA

DESIGN FOR A CASING FOR A NAIL POLISHING MACHINE

Application filed November 20, 1931. Serial No. 41,791. Term of patent 3½ years.

To all whom it may concern:

Be it known that I, REX R. WAGGONER, a citizen of the United States, residing at Santa Monica, in the county of Los Angeles and State of California, have invented a new, original, and ornamental Design for a Casing for Nail Polishing Machines, of which the following is a specification, reference being had to the accompanying drawings, forming part thereof.

I claim:

The ornamental design for a casing for nail polishing machine, as shown.

REX R. WAGGONER.
